LATHING

Albert C. Karelus, Altadena, Calif.

Application May 15, 1944, Serial No. 535,615

8 Claims. (Cl. 72—116)

This invention relates to lathing of the general character embodied in my co-pending applications Serial Nos. 488,151 and 493,644, filed on May 24, 1943, and July 6, 1943, respectively.

In their broad aspects, the above identified applications disclose lathing composed of a backing member or other suitable flexible material having plaster keying openings therethrough, and associated with a welded metal fabric formed by intersecting first and second wires on the plaster-receiving side of the member, and a third set of wires on the other side of the member welded through the aforesaid openings to certain of the wires of the metal fabric, to provide wire reinforcing means which becomes embedded in plaster when applied to the lathing.

The primary object of the present invention is to provide a lathing of the above described general character whose structure is simplified by the elimination of certain elements and the utilization of the remaining elements in a manner to satisfactorily perform the functions of the greater number of elements, all to the end of greatly reducing the manufacturing costs while maintaining the structural strength required for class A work as identified by building codes, and enabling a continuous wire mesh reinforced all-purpose lathing to be installed not only in the higher priced structures, but also in low cost buildings wherein non-reinforced lathing such as plaster board and wood lath would otherwise be used.

More specifically, it is another object of the present invention to provide a simplified construction of lathing composed of a minimum number of elements consistent with the necessary functions to be performed, and including a backing member of flexible sheet material such as strong, tough paper, and metallic reinforcement composed entirely of first wires on one side of the backing member, and second wires on the other side of the backing member in intersecting or meshed relationship to the first wires, with the first and second wires being welded together at their intersections, through openings in the backing member which are of such contour and relationship to each other and to the wires as to expose the latter for the application of mortar thereto throughout their entire lengths from one side of the backing member, to thus provide practically the same plaster-embedded continuous wire reinforcement as would be obtained by the use of a mesh fabric without a backing member, all with the added advantage of the interposed backing member in presenting a flexible foundation which yields sufficiently to troweling pressure to insure embedding of the first and second wires in plaster without wasting plaster by areas of excessive plaster thickness.

A further object of the invention is to provide a lathing of the above described character in

which the first and second intersecting wires forming the entire reinforcement and being completely embedded in plaster, render the latter equally strong in two directions. In addition, the relatively narrow webs of backing sheet material remaining between the confronting ends of the elongated openings or slots in the backing sheet, permit the portions of plaster which are forced through the openings to flow together and form continuous keys or ribs, thus increasing the rigidity of the finished product. Also, the novel arrangement of the two-wire type of reinforcement with respect to the backing sheet enables the lathing to be secured to building studs by nailing around one series of wires while the other series of wires remains free on the plaster-receiving face of the backing sheet for maximum embedding of the plaster to produce a continuous reinforcement.

20 A still further object of this invention is to provide a wire mesh-reinforced lathing in which the webs of material between the ends of the openings in the backing sheet are pre-grooved to receive the back wires of the mesh reinforcement, in a manner to space the sheet away from the front wires and provide an excess of backing sheet material, all to the end of enabling the wires to be more deeply and uniformly embedded in the plaster, as well as confining the backing sheet against displacement laterally of the back wires in order that the latter will be maintained by the grooves, properly centered in the openings along the lengths thereof prior to the application and setting of the mortar.

25 35 With these and other objects in view, the invention resides in the combinations, arrangements and functional relationships of elements as set forth in the following specification and particularly pointed out in the appended claims.

40 In the accompanying drawings,

Figure 1 is a view in front elevation, of the form of lathing embodying the present invention and applied to members of a building frame;

45 Figure 2 is a view in rear elevation, of the lathing installed as in Figure 1;

Figure 3 is a reduced scale view of the lathing in rear elevation, after the plaster has been applied to the lathing;

50 Figure 4 is an enlarged fragmentary sectional view taken on the line 4—4 of Figure 3;

Figure 5 is an enlarged fragmentary sectional view taken on the line 5—5 of Figure 1;

55 Figure 6 is a view similar to Figure 5, but showing the lathing after a coat of plaster has been applied thereto;

Figure 7 is an enlarged fragmentary sectional view taken on the line 7—7 of Figure 1;

60 Figure 8 is a view similar to Figure 7, but showing the lathing after a coat of plaster has been applied thereto;

Figure 9 is a fragmentary detail sectional view of the backing sheet.

Referring specifically to the drawings, the invention in its broad aspect consists of a backing member B and a plaster-reinforcing metal fabric F.

The backing member B is preferably constructed from strong, tough paper or similar flexible sheet material, and is cut into rectangular sheets of a predetermined standard size. The member B is formed throughout its area with elongated openings or slots 10 arranged in parallel rows extending longitudinally and transversely of the member and at equal center to center distances in both directions, which in practice may be from one and one-half to two inches as examples. It will be particularly noted that the confronting ends of successive openings of the horizontal rows as illustrated for a vertical wall, are in close proximity to each other so as to leave only a narrow web 11 of backing sheet material therebetween which in practice can be as little as three-sixteenths or one eighth of an inch. It is also to be noted that during the operation of punching the openings 10 through the backing sheet, the portion of the latter defining the narrow connecting webs 11 is subjected to a forming operation by suitable mechanism (not shown), sufficient pressure being imposed upon the webs to form lateral offsets or grooves 12 therein on the rear face of the backing sheet. These grooves 12 are coincident to the longitudinal center line of the openings 11, and open through the ends of the openings as well as through opposite edges of the backing sheet. By preforming the grooves 12 in the backing sheet, the relatively stiff paper stock from which the sheet is constructed, is rendered more pliable and yieldable, by slightly breaking down or deforming the fibrous structure of the paper across the webs. Furthermore, the forming of the grooves 12 provides an excess of backing sheet material for coaction with the metal fabric F in a manner to be later described.

The plaster reinforcing metal fabric F is composed entirely of two right angularly intersecting series of wires 15 and 16 between which the backing sheet is interposed. The wires of the two series form a mesh corresponding to the center to center distance between the openings 10, and are welded or otherwise permanently secured together at their intersections in the centers of the openings 10 as indicated at 17, thus making a unitary structure in which the front wires 15 are arranged in parallel rows and span the openings 10 transversely thereof on one side of the sheet.

The parallel rear wires 16 span the openings 10 longitudinally of the latter, with these wires extending along the grooves 12 and seating therein as shown in Figure 5, so that the front face of the backing sheet will be originally spaced from the wires 15 as clearly shown in this figure. The grooves 12 also co-act with the wires 16 to prevent the backing sheet and fabric from shifting relatively in a direction transversely of the lengths of the openings 10, and thus maintain the wires 16 centered in the openings.

The completed lathing as above described is preferably secured every six inches or less to building frame members M by the "nail on" or "tie on" method, around only the wires 16 so as to leave the front wires 15 entirely free of the lathing securing means 18 shown in Figure 1.

Assuming that a number of sheets of the lathing are to form a wall foundation, and that the

sheets are secured to the frame members M with the edges of successive sheets overlapped as shown in Figure 1, and with the lengths of the openings 10 and hence the wires 15 extending horizontally, mortar is troweled against the front face of the backing sheet by a first upward stroke and then generally horizontal back and forth spreading strokes to level out the outer surface of the mortar.

Due to the effect of the grooves 12 of the webs 11 in providing an excess of backing sheet material between points of nailing to the supports M, the backing sheet is readily forced further away from the vertical wires 15 under the normal troweling pressure of mortar against the sheet. In practice, the backing sheet is forced about one eighth of an inch back from the wires 15 so as to be disposed beyond the rear wires 16 as shown in Figure 8, to thus embed the wires 15 throughout their entire lengths approximately one eighth of an inch in the mortar as shown in this figure. Furthermore, the extremely long openings 10 facilitate the rearward displacement of the backing sheet by troweling pressure, as the sheet is held against such displacement only by the narrow webs 11 bearing against the wires 16, to thus embed the wires 15 substantially uniformly in mortar, with the result of producing a uniformly strong bond between the wires and plaster.

Mortar is also forced under the troweling pressure and strokes through the openings 10 in sufficient quantity to not only provide plaster keys, but to also bridge the narrow webs 11 of backing sheet material remaining between the ends of successive openings 10, to thus also embed the wires 16 throughout their entire lengths in mortar, and thereby create continuous reinforced plaster ribs or keys 20 from one building frame member M to the next one as shown in Figure 3.

By completely embedding the entire two-wire mesh fabric in plaster, the latter is uniformly reinforced in both horizontal and vertical directions, and is further strengthened and rendered more rigid by the continuous ribs 20. It is preferable in practice to use a larger size for the horizontal wire 16 than for the vertical wire 15, such as No. 13 or 14 gage for the former, and No. 15 gage for the latter, to further stiffen the structure against sagging between vertical supports.

It will be noted that the long side edges of the openings 10 act to slice mortar from the trowel during the first upward stroke thereof so as to facilitate the application of the mortar. The wires 15 and 16 are entirely free of kinks, and remain straight irrespective of the presence of the webs 11 whose grooves 12 offset the backing sheet from the wires 16, all to the end that the wires will have maximum strength against elongation, with the result of providing the desirable flat foundation for the plaster.

From the foregoing description it will be manifest that the lathing is composed of the minimum number of elements, (1) the backing member B, and (2) the two-wire mesh fabric F between whose longitudinal and transverse wires 15 and 16 the backing sheet is interposed, and that the backing sheet is structurally characterized by the specifically constructed and functionally related openings 10 and intervening webs 11 with their grooves 12 enabling the entire lengths of the two wires 15 and 16 to become embedded in plaster to provide substantially uniformly strong reinforcement in two directions throughout the area of the lathing.

It will also be appreciated that this simplified construction more efficiently performs all the functions of more complicated lathing structures, and that its manufacturing cost is materially less, due to the fact that only a single welding operation of the wires 15 to the wires 16 through the openings 10 of the interposed backing member to complete the metal fabric F and assemble the latter and backing member is necessary as compared to two or more welding operations necessary in lathing of the same general character heretofore proposed.

I claim:

1. Lathing of the class described comprising: a backing member of flexible sheet material having elongated openings therethrough, and arranged in parallel rows; a metal reinforcing fabric composed entirely of parallel spaced front wires on one side of the sheet spanning said openings transversely thereof, and parallel spaced back wires on the other side of the sheet spanning said openings longitudinally thereof; and means permanently securing the said wires together at their intersections in said openings.

2. Lathing of the class described comprising: a backing member of flexible sheet material having elongated openings therethrough, and arranged in parallel rows; a metal reinforcing fabric composed of spaced parallel front wires on one side of the sheet spanning said openings transversely thereof, and spaced parallel back wires on the other side of the sheet spanning said openings longitudinally thereof; and means permanently securing said wires together at their intersections in said openings; said openings being in end to end relation in their rows of one direction and being sufficiently long to leave only relatively narrow webs of backing sheet material between the ends of successive openings, rendering the backing sheet material free to be forced away from the front wires throughout their lengths and rearwardly beyond the plane of the back wires, under troweling pressure of mortar against the backing sheet, whereby to enable the front wires to become completely embedded in mortar throughout their lengths, and the back wires to become embedded in mortar.

3. Lathing of the class described comprising: a backing member of flexible sheet material having elongated openings therethrough, and arranged in parallel rows; a metal reinforcing fabric including spaced parallel front wires on one side of the sheet spanning said openings transversely thereof, and parallel spaced wires on the other side of the sheet spanning said openings longitudinally thereof; and means permanently securing said wires together at their intersections in said openings; said openings being in end to end relation in their rows of one direction with the confronting ends of successive openings in proximity to each other enabling mortar forced through the openings by troweling pressure to flow together into continuous ribs completely covering the back wires with mortar throughout their lengths.

4. Lathing of the class described comprising: a metal reinforcing fabric consisting entirely of two series of wires in right angular relation and welded together at their intersections; and a flexible backing sheet having openings therethrough and interposed between the two series of wires so that the wires of one series are on one side of the sheet, and the wires of the other

series are on the other side of the sheet with the wire intersections in said openings.

5. Lathing of the class described comprising: a metal reinforcing fabric consisting entirely of two series of wires in right angular relation and welded together at their intersections; and a flexible backing sheet having openings therethrough, and interposed between the two series of wires so that the wires of one series are on one side of the sheet, and the wires of the other series are on the other side of the sheet with the wire intersections in said openings; said openings being relatively long and narrow, with confronting ends of the openings leaving only narrow webs of backing sheet material therebetween so that the backing sheet will be sufficiently weakened at such webs to be forced by troweling pressure of mortar entirely away from the wires of one series in order to embed such wires in mortar throughout their entire lengths; said confronting ends of openings being in such close proximity that mortar forced through the openings will tend to join across the webs in substantially continuous keys in which the wires of the other series will be embedded.

6. Lathing of the class described comprising: a backing sheet of flexible material having elongated openings therethrough arranged end to end in parallel rows and leaving relatively narrow webs of backing sheet material between the ends of successive openings; wires spanning the openings transversely thereof on one face of the backing sheet; and other wires spanning the openings longitudinally thereof on the other face of the sheet and welded to the first said wires at the intersections of the wires in said openings; said webs having grooves in which the second said wires are received to space the backing sheet from the first said wires.

7. Lathing of the class described comprising: a backing sheet of flexible material having elongated openings therethrough arranged end to end in parallel rows and leaving relatively narrow webs of backing sheet material between the ends of successive openings; wires spanning the openings transversely thereof on one face of the backing sheet; and other wires spanning the openings longitudinally thereof on the other face of the sheet and welded to the first said wires at the intersections of the wires in said openings; said webs having grooves in which the second said wires are received to space the backing sheet from the first said wires; said grooves being of sufficient depth to provide an excess of backing sheet material between said rows of openings and to confine the backing sheet against planar displacement laterally of the second said wires.

8. Lathing of the class described comprising: a backing sheet of flexible material having elongated openings therethrough arranged end to end in parallel rows and leaving relatively narrow webs of backing sheet material between the ends of successive openings; wires spanning the openings transversely thereof on one face of the backing sheet; other wires spanning the openings longitudinally thereof on the other face of the sheet and welded to the first said wires at the intersections of the wires in said openings; and means co-acting with the backing sheet and second said wires to dispose the backing sheet in spaced relation to the first said wires and to provide an excess of backing sheet material between said rows of openings for the purpose described.

ALBERT C. KARELIUS.
